WAX APPLICATOR

Ralph C. Kersh, Mishawaka, Ind., assignor, by mesne assignments, to S. C. Johnson & Son,
Inc., Racine, Wis., a corporation of Wisconsin

Application October 16, 1948, Serial No. 149,142

Term of patent 14 years

(Cl. D9—2)

To all whom it may concern:

Be it known that I, Ralph C. Kersh, a citizen of the United States residing at Mishawaka, in the county of St. Joseph and State of Indiana, have invented a new, original, and ornamental Design for a Wax Applicator, of which the following is a specification, reference being had to the accompanying drawing, forming part thereof.

Figure 1 is a fragmentary perspective view of a wax applicator, showing my new design with the handle broken away for convenience of illustration.

I claim:

The ornamental design for a wax applicator, as shown.

RALPH C. KERSH.
